UNITED STATES PATENT OFFICE.

ROSCOE S. HEISE, OF MIDDLETON, OHIO.

ELECTRIC OVEN.

Application filed July 8, 1926. Serial No. 121,145.

This invention relates to electric ovens, stoves and the like, and is fully described in the following specification and shown in the accompanying drawings, in which:

5 Figure 1 is a front elevation of an electric oven embodying the invention;

Fig. 2 is a side elevation of the same showing the side wall partly broken away and showing the door carrying mechanism in 10 closed position;

Fig. 3 is a similar view of the same showing, in full line position, the door withdrawn from the oven in dotted line position, the door lowered;

15 Fig. 4, is an enlarged vertical section on the line 4—4 of Fig. 1; and

Fig. 5 is a transverse section on the line 5—5 of Fig. 4.

The embodiment illustrated comprises an 20 oven having a hollow sheet metal rear wall 10, side walls 11 and 12, bottom 13 and top 14 secured together as by means of screws 15 and 16 and supported upon legs 17.

A sheet metal front 18 is secured therein 25 and has a large rectangular opening which is surrounded by the door frame 19 preferably of cast iron which is secured to the front plate 18.

The oven proper 20 is made up of an oven 30 back 21, a front flange 22 and a center portion 23 which are secured together by lapped joints as shown in Fig. 4. The center portion 23 is also preferably made up of four pieces; namely, side members 24 and top and bottom members 25 and 26 respectively which are likewise secured together by means of lapped joints 27 and 28. The one-piece flange 22 is enlarged at 22^a to receive the door as will later be explained and terminates in an outwardly 40 extending flange 22^b which is securely held between the door frame 19 and the front plate 18, as by means of screws or rivets, not shown.

Omitting for the present the mechanism for carrying the door, it consists essentially of 45 a front door plate 29 and a pressed metal plate 30 having a flange 30^a by which it is secured to the front door plate 30 by means of screws 31.

Within the door is a series of castings 32, 50 each of which occupies substantially one-fourth of the space and these are provided with ribs 33 which are screw-threaded as shown in Fig. 4 to receive the conical nut 34 which serves to expand them out against the metal 30^b forming the edge of the threaded hub 35. Thus an adjustment is provided

which permits the operating lever 37 to be set so that it will extend at any angle which the operator desires. It is preferably so made however that it will stand in the vertical position shown in Fig. 3 when the door is unlocked so as to be released and is preferably held in this position by means of balls 40 on the spring 41.

Thus it will be seen that when the door is 65 forced in to the position shown in Fig. 4, the operator turns the lever 37 forcing the castings 32 outwardly thereby firmly gripping the sheet metal members 30^b and 22 between the castings 32 and the door frame 19. Keys 70 42 are placed between the castings 32 and lie flush with the same so that pressure is exerted substantially uniform upon the adjacent metal members 22^a and 30^b.

Ears 43 and 44 are secured at each side of 75 the door. The ear 44 is pivotally secured at 45 to the end of the Z-bar 46 which is pivotally suspended at 47 and 48 on parallel links 50 and 51. The ends of these links in turn are pairs of parallel links 52, 53 and 54, 55. 80 The links of each of these pairs are substantially the same and their pivot points are so located so as to keep members of each pair of links parallel at all times.

The ear 43 is pivotally connected to a rod 85 56 which is pivotally connected to the upper end of a lever 57 which is pivotally connected at 58 to the Z-bar 46. The lever 57 carries a plate 59 to which is pivotally connected a rod 60 at the point 61, this rod passing 90 through an opening 62 in the bottom plate 13 and carrying a washer 63 which compresses a spring 64 which is mounted on the rod 60.

Thus it will be seen that when the door is 95 pulled outwardly from the closed position of Fig. 2, to the open position of Fig. 3, the rod 56 and lever 57 do not move with respect to the Z-bar 46, but the whole is carried outwardly by the parallel link motion previously described. A comparison of the positions of 100 these links in Figs. 2 and 3 will make this clear, and it will also be observed that the opening 62 is so placed that the spring 64 assists in closing the door as shown in Fig. 2 when it has gone in a predetermined amount 105 and it likewise assists in forcing the door outwardly when the door has been moved out beyond the dead center as shown in Fig. 3.

It will be understood, of course, that the 110 system of links and levers previously described and shown in Figs. 2 and 3 is duplicated on the opposite side of the oven lining.

Having drawn the door outwardly to the position shown in Fig. 3 by this straight line mechanism, the operator continues to move the door outwardly as by pulling on the lever 5 37 which now swings the door about the pivots 45 at each side. The link 52 has an extension 52^a which extends across to the opposite side and this serves to keep the links of the two sides in about the same relative positions at all times so that any force maintained to open and close the door if exerted at one side of the center of the door will be transmitted from the mechanism of one side to that of the other so as to prevent one side 10 of the door moving in or out in advance of the other.

As the door swings down about the pivots 45 the rods 56 are drawn from the full line position to the dotted line position of Fig. 3 20 when the door now assumes a horizontal position with the now horizontal surface of the door substantially on a level with the bottom of the line of the oven so that cooking utensils or the like in the oven may be readily 25 drawn out on the horizontal surface of the door. To accomplish this the rods 56 are pivotally connected as has been previously stated, to levers 57 which in turn are pivotally connected to the Z-bars 46. As the door 30 is swung down the rods 56 cause the levers 57 and plates 59 to swing to an angle of 90° from the full line position to the dotted line position in Fig. 3. Thus the rod 60 by this movement again passes through dead center so that 35 the springs 64 serve to maintain the door in both the raised and lowered position.

For the convenience of the operator a thermometer 65 of any suitable type is secured in the door and extends through it so 40 as to be visible in front of the oven. On the front of the oven are also three controlling switches 66 which serve to control the amount of current passing through the heating elements of which there are three, one, 67 being 45 placed in the top of the oven, one 68 in the bottom of the oven and the other 69 on the top of the casing. These heating elements are not shown in detail as they are well known in the art, nor have I shown the connections 50 between these heating elements and the source of current supply.

The door closing mechanism is so nearly airtight that a relief valve 70 is required and this is inserted in the back as shown in 55 Fig. 4. This is a spring operated device which is so made as to permit a small excess of pressure about atmospheric to escape outwardly therethrough and likewise when a vacuum within the oven chamber occurs 60 during the time when it is cooling off, air will be permitted to enter through this same relief valve.

The sides 30^b of the door are preferably 65 tapered slightly as is also the flange 22^a so as to permit the door to be opened and closed

more easily. A depression 22^b around the flange 22^a catches any moisture which collects on the walls.

Attention is particularly drawn to the construction of the chamber in which the longitudinal seams 27 and 28 are headed into the two parallel transverse beads 27^a and 27^b. 70

In operation, the vessel containing the material to be cooked is placed in the oven, 75 preferably on racks, not shown, and electric current is turned on by means of the switches 63 and left on a predetermined degree of heat when the electric current is shut off. Cooking then proceeds on the contained heat. To assist in retaining this heat, any suitable insulation such as mineral wool (not shown) 80 may be interposed between the oven proper and the outer shell 10.

While I have shown and described but a single embodiment of this invention, it is to 85 be understood that it is capable of many modifications. Changes therefore in the construction and arrangement may be made which do not depart from the spirit and scope 90 of the invention as disclosed in the appended 95 claims.

I claim:

1. In an electric oven, an oven chamber closed except for an opening at one vertical side, a door adapted to close said opening, 95 and mechanism for carrying said door into said opening parallel to itself, said mechanism being movable to lower said door from a vertical position to a substantially horizontal position and to maintain it in either of 100 these positions.

2. In an electric oven, an oven chamber closed except for an opening at one vertical side, a door adapted to close said opening, 105 and mechanism for carrying said door into said opening parallel to itself, said mechanism being movable to lower said door from a vertical position to a substantially horizontal position on a level with the bottom of the oven chamber and to maintain it in either of 110 these positions.

3. In an electric oven, an oven chamber closed except for an opening at one side, a door adapted to close said opening, and mechanism for carrying said door into said opening parallel to itself, said mechanism being movable to lower said door to a substantially horizontal position, said mechanism comprising means for forcing said door toward an open or a closed position when it has passed 115 a predetermined point.

4. In an electric oven, an oven chamber closed except for an opening at one side, a door adapted to close said opening, and a system of parallel links for carrying said door 125 into said opening parallel to itself, said system of parallel links being movable to lower said door to a substantially horizontal position.

5. In an electric oven, an oven chamber 130

- closed except for an opening at one side, a door adapted to close said opening, and a system of parallel links at each side of the oven, the links at the two sides being operatively connected together for carrying said door into said opening parallel to itself, said system of parallel links being movable to lower said door to a substantially horizontal position.
10. 6. In an electric oven, an oven chamber closed except for an opening at one side, a door adapted to close said opening, said door having a sheet metal cover and means in said door for expanding said cover outwardly into engagement with said opening.
7. In an electric oven, an oven chamber closed except for an opening at one side, a door adapted to close said opening, said door having a sheet metal cover means for carrying said door, and means in said door for expanding said cover outwardly into engagement with said opening.
20. 8. In an electric oven, an oven chamber closed except for an opening at one side, a door adapted to close said opening, a reinforcing member surrounding said opening, said door having a sheet metal cover, expansible members within said door for pressing said cover into engagement with said opening, and means for forcing said expansible members outwardly to lock and seal said door.
25. 9. In an electric oven, an oven chamber closed except for an opening at one side, a door adapted to close said opening, a reinforcing member surrounding said opening, said door having a sheet metal cover, expansible members within said door for pressing said cover into engagement with said opening, and a tapered screw having a handle extending outside said door for forcing said expansible members outwardly to lock said door.
30. 10. In an electric oven, an oven chamber closed except for an opening at one side, a door adapted to close said opening, a reinforcing member surrounding said opening, said door having a sheet metal cover, expansible members within said door for pressing said cover into engagement with said opening, and a tapered screw having a handle extending outside said door for forcing said expansible members outwardly to lock said door, said handle being adjustable so as to be set at any desired angle.
35. 11. In an electric oven, an oven chamber having a sheet metal lining closed except for an opening at one side, a door adapted to close said opening, said door having a sheet metal cover adapted to fit the opening in said lining, and means for expanding said sheet metal cover into contact with said sheet metal lining to lock and seal the same.

55. 60. ROSCOE S. HEISE.
